UNITED STATES PATENT OFFICE.

NIIS D. LEVIN, OF COLUMBUS, OHIO, ASSIGNOR TO THE JEFFREY MANUFACTURING COMPANY, OF COLUMBUS, OHIO, A CORPORATION OF OHIO.

COAL-MINING MACHINE.

Application filed September 11, 1918, Serial No. 253,632. Renewed July 31, 1925.

To all whom it may concern:

Be it known that I, NIIS D. LEVIN, a citizen of the United States, residing at Columbus, in the county of Franklin and 5 State of Ohio, have invented certain new and useful Improvements in Coal-Mining Machines, of which the following is a specification, reference being had therein to the accompanying drawing.

10 The present invention relates to certain new and useful improvements in coal mining machines, and particularly to that class of machines whereby coal is dislodged from its native bed, transported rearwardly 15 of the machine and loaded into conveniently placed cars for removal from the mine.

The especial object of this invention is to provide in a machine of the class described, improved devices by which fragments of 20 coal are broken down from the mass of the vein and transported rearwardly of the machine.

The devices by which I attain this object are fully set forth in the following 25 specification reference being had to the accompanying drawings of which—

Figs. 1 and 2 constitute a plan view of the preferred embodiment of my invention.

Figs. 3 and 4 constitute a side elevation of 30 the machine illustrated in Figs. 1 and 2.

Fig. 5 is a section along the line 5—5 of Fig. 3.

Fig. 6 is a section along the line 6—6 of Fig. 1.

Fig. 7 is a section along the line 7—7 of 35 Figs. 1 and 2.

Fig. 8 is a detail of the feed rope guide sheaves.

Fig. 9 is a section along the line 9—9 of 40 Fig. 2.

Fig. 10 is a section along the line 10—10 of Fig. 2.

Fig. 11 is a section along the line 11—11 of Fig. 1.

45 Like numerals refer to similar parts in the several figures.

Speaking broadly this machine comprises a bottom pan adapted to rest upon and slide in any direction over the floor of the mine and to be anchored in fixed relation to the coal face during the operation of the machine. Upon this bottom pan is mounted a turn table adapted to rotation in either direction, and constituting the main frame

upon which the operative parts of the machine are mounted. These operative parts consist of a cutting mechanism adapted to form a kerf above, behind and below a section of the coal vein, breaking down and gathering devices by which fragments of coal are broken off from the partially severed section and transferred to the loading devices by which these broken off fragments are deposited in conveniently placed cars for transportation from the mine, and power devices by which the several elements of the machine are actuated.

In the drawings the numeral 1 indicates as an entirety, the bottom pan which is adapted to rest directly upon the floor of the mine. This pan consists of a rectangular steel plate 2 the edges of which are turned upward, as indicated at 3, to facilitate its sliding in any direction over the floor of the mine. The plate 2 is stiffened by longitudinally extending steel bars 4 and by an annular angle bar 5 all of which are electrically welded to the upper surface of the plate. At its forward end the plate 2 is semicircular in form and the annular stiffening angle bar 5 is positioned adjacent to and concentric with this end of the plate. Concentric with the annular angle bar 5 is a pivot bearing casting 6 which engages a downwardly projecting pivot post 7 of the main frame casting 8 to prevent its lateral displacement relative to the pan. Attached to the plate 2, in a concentric circle outside of the stiffening angle bar 5, is a plurality of bearing brackets 9 in which are mounted the antifriction bearing rollers 10. The main frame casting 8 is supported directly upon these rollers 10 and constitutes a turn table, adapted to rotation in either direction, upon which the operative parts of the machine are mounted.

Attached to the main frame 8 is an electric motor 12, arranged to actuate the machine, and I have indicated at 13 a controlling mechanism, having an operating handle 14 convenient to the hand of the operator, by which the operation of the motor may be controlled. The motor 12 is connected with the controller 13, and also with any convenient source of electric power, by suitable electric conductors which are not shown in the drawings as they form no part of the present invention and are well un-

derstood by persons skilled in the art. For purposes of illustration I have shown an electric motor, but it is to be borne in mind that any type of motor may be employed which is suitable to the conditions under which the machine operates.

Formed on the frame of the motor 12 are journal bearings 15 in which are rotatably mounted the trunnions 16 and 17 of the cradle casting 18 upon which is carried the cutting mechanism and the gathering mechanism of the machine, as will hereinafter appear. Journaled in a bearing formed in the trunnion 17 and in a second bearing 19 supported on a pedestal of the main frame 8, is a transverse power shaft 20 from which the several elements of the machine are actuated and which is itself driven from the motor 12 through the spur gear 21 and the armature pinion 22.

The cutting mechanism comprises a vertically disposed loop shaped cutter frame 23 upon which travels an endless cutter chain 24 having renewable cutter bits 25 adapted to cut a kerf in the coal body above, behind, and below sections of the coal vein to entirely sever them from the mass of the vein. The cutter chain 24 is of a type well known in the mining machine art, consisting of alternate strap and block links, and is engaged by a sprocket wheel 26, mounted upon the power shaft 20. Upon the hub of the sprocket wheel 26 are formed clutch teeth 27 adapted to engage with similar teeth of the clutch member 28 splined to the shaft in a manner common to such clutches.

The cutter frame 23 is formed of a steel bar 31, of rectangular cross section, to the sides of which are attached the plates 32 the projecting edges of which form the guide ways in which the chain 24 travels. The rectangular bar 31 is bent to form a loop and is secured at both ends to the vertical plate 33 which is attached to a flange of the cradle casting 18. In order to facilitate handling the machine in the mine, the vertical width of the cutter frame 23 is made less than the total height of the coal vein which is to be removed, and this cutter frame is adapted to rotary movement about the trunnions 16 and 17 and is so formed that when in its lower position of adjustment the lower side 34 of the loop will be parallel with the general direction of the coal seam at the line of the mine floor, to remove the lower portion of the coal vein, and when in its elevated position the upper side 35 of the loop will be parallel with the general direction of the coal seam at the line of the roof of the mine to remove the upper portion of the vein. When the mining machine is placed adjacent the coal face, and the turn table 8 is rotated in a direction to cause the cutter bits 25 to engage the

coal face, there will be formed a loop shaped kerf extending above, behind and below a section of coal, entirely severing said section from the body of the vein. After the upper portion of the coal has been removed the cutter frame may be rotated upon the trunnions 16 and 17 to its lower position of vertical adjustment, as indicated by the dotted lines in Fig. 4, and a second cut made to remove the remainder of the vein. The vertical movement of the cutter bar may be accomplished in any preferred manner. In the drawings I have illustrated a hydraulic jack 36 connected to the main frame casting 8 at 37 and to the cradle casting 18 at 38. A pump 39 actuated by an eccentric 40 attached to the power shaft 20 supplies the pressure to actuate the jack. As these devices form no part in the present invention further description of them is not thought to be required at this time.

In a great many veins of coal the natural cleavages cause the severed blocks to break off into smaller fragments of suitable size to be conveniently transported from the mine, while in other veins the coal has a tendency to hang and special devices must be provided to insure its breaking down. In the present machine I have provided combined breaking and loading mechanism adapted to insure the breaking down of the coal and to receive the fragments as they are broken down and remove them rearwardly of the machine.

The loading mechanism comprises a receiving conveyer having a forward portion extending parallel with and in the same horizontal plane as the lower side of the cutter frame, in position to receive the coal as it is severed from the body of the vein, and a rearward portion inclined upwardly to discharge said severed material into a loading conveyer by which it is delivered to cars conveniently placed upon the mine track at the rear of the machine.

The receiving conveyer is of a well known type having an endless chain 41 adapted to travel in the guide ways 42 and 43 and having laterally extending flights 44 adapted to engage the coal to move it along a suitable trough 45. The guide ways 42 and 43 are formed of longitudinally extending angle bars 46 and 47 which are held in spaced relation by suitable cross members to constitute a supporting frame work for the conveyer. At the rearward end of the conveyer the angle bars 46 and 47 are attached to a yoke casting 48 in which are formed journal bearings 49 and 50 which support the vertical shaft 51. To the shaft 51 is attached a sprocket wheel 52 which engages the conveyer chain 41 to drive it. Formed on the lateral extension 53 of the yoke casting 48 are journal bearings 54 and 55 which engage the outer surface of the hubs 56 which support the vertical shaft 51.

56 of the bracket castings 57 to form a hinge support upon which the conveyer frame may be rotatably adjusted. Formed in the hubs 56 of the bracket castings 57 are journal bearings in which is mounted a horizontal shaft 58 having a bevel pinion 59 which engages with the bevel gear 60 attached to the vertical shaft 51. An out-board bearing 61 formed on the yoke casting 48 affords additional support to the shaft 58 and insures the proper meshing of the gears. Rotatably mounted upon the shaft 58 is a sprocket wheel 62 which is in alignment with the sprocket wheel 63 upon the power shaft 20. The sprocket wheels 62 and 63 are connected together by a suitable driving chain 64. The sprocket wheel 62 is adapted to be connected with the shaft 58 through a multiple disk friction clutch 65 arranged to be controlled by the hand wheel 66 which is within convenient reach of the hand of the operator. By the arrangement of parts just described the conveyer may be operatively connected with the motor 12. The bracket castings 57 being secured to the frame of the motor 12 affords support for the conveyer from the main frame casting 8.

To the angle bars 46 of the guide ways 42 is attached a plate 67 which forms the bottom of the conveyer trough 45 and suitably supported side plates 68 confine the material in the trough. To the angles 47 of the guide ways 43 is attached a plate 69 which affords a slide way for the support of the conveyer flights 44 of the return strand of the conveyer and longitudinal angle bars 70 are suitably disposed to protect these flights from accidental contact with the person of the operator. At their forward ends the guide ways 42 and 43 are connected by a horizontal hinge 71 with extension guide ways 72 and 73. At their forward end these extension guide ways 72 and 73 are attached to a foot casting 74 having a semicircular guide surface 75 around which the conveyer chain 41 slides. Provision is made for the adjustment of the tension of the conveyer chain 41 by the longitudinal movement of the foot casting 74 relative to the extension guide ways 72 and 73 by means of the adjusting screw 76 in the manner common to conveyer practice. To the extension guide ways 72 and 73 is attached a plate 77 extending laterally and forwardly to afford a sliding support for the conveyer flights 44. The plate 77 is extended laterally towards the cutter bar 23 and constitutes the apron upon which the coal is received as it is dislodged from the body of the vein. Along the advancing edge of the apron 77 are downwardly projecting lugs 78 which engage the flange 79 of the cutter arm to support the apron and maintain its operative relation with the cutter

bar. Along the edge of the apron 77, remote from the cutter bar, is attached a channel bar 80 which serves to stiffen the apron and to support the protecting plate 81 by which the conveyer flights are guarded from accidental contact with the person of the operator. As the center of vertical rotation of the conveyer is considerably removed from the center of vertical rotation of the cutter bar there will result, when the parts 75 are vertically adjusted, a variation of relation between the receiving apron 77 and the lower side 34 of the cutter arm. This variation of relation is provided for by the sliding contact of the lugs 78 upon the flange 80 79 and by the flexibility of the conveyer frame at the hinge 71. A bracket 82 extending forwardly from the cradle casting 18 engages the hinge 71 to support the forward part of the conveyer frame and by means 83 of this support the conveyer and the receiving apron are elevated and depressed with the cutter arm by the actuation of the hydraulic jack 36.

In practice it is commonly preferable to remove the upper portion of the vein first and afterwards to lower the cutting mechanism and remove the remainder of the vein. When the cutter arm is in its elevated position its lower side 34 will be inclined upwardly resulting in the formation of a conical surface in the lower kerf. I have, therefore, curved the plate 77 upwardly along transverse lines, as indicated in Fig. 10, so that it shall conform approximately to this conical surface of the coal thereby avoiding the cramping of the parts and the undesirable friction of the conveyer structure upon the coal.

During the operation of the machine, as the cutter arm 23 is rotated about the center 7 of the turn table, the cutter bits 30 form a kerf in the coal body above, behind and below a crescent shaped section of coal to completely sever it from the body of the vein. At the thinner parts of this section, near the ends of the crescent, the natural cleavage crevices of the coal cause it to break down in fragments of convenient size to be removed by the conveyer. At its middle, however, this section is of such thickness that the natural cleavages cannot be depended upon to break down the coal and I have provided auxiliary devices associated with the loading conveyer to insure the breaking down of the coal thereby guarding against the partly severed section overhanging to such an extent that its rearward end will abut against the frame work of the conveyer producing undesirable strains both in the conveyer structure and in the feeding mechanism. Formed upon the conveyer flights 44 are upwardly projecting sockets 83 in which are mounted cutter bits 84 similar to those used on the cutter chain. As the conveyer flights

95

100

105

110

115

120

125

130

44 travel, around the foot casting 74 these bits 84 will engage the overhanging end of the partially severed sections of coal and pry off fragments therefrom, thereby insuring the breaking up of the coal into fragments of suitable size for removal by the conveyer.

Pivottally mounted upon a circular extension 85 of the main base casting 8 is the 10 loading conveyer 86 which is adapted to receive material from the receiving conveyer and discharge it into a car 87 suitably placed upon the mine tracks in the rear of the machine. At its forward end the conveyer is 15 attached to and supported by a steel plate 88 having a hub casting 89 secured to its center. Through the hub casting 89 extends a pivot pin about which the conveyer is rotatable. The pivot pin 90 has a broad head 20 91 which engages the upper surface of the hub casting 89 and at its lower end it is provided with a suitable nut 92 to resist the upward thrust upon the pin. Upon the base extension 85 is mounted a plurality of 25 rollers 93 upon which the plate 88 bears as a fulcrum to support the overhanging weight of the conveyer. The conveyer 86 is provided with an auxiliary motor 94 by which it is actuated independently of the 30 motor 12. The conveyer 86 comprises a trough 95 along which the material is propelled by a plurality of cross bars 96 extending between two parallel endless chains 97 which are adapted to travel in guide ways at 35 the sides of the conveyer trough in a manner well known in conveyer practice, but as the details of this conveyer form no part of the present invention further description is not thought to be required at this time.

40 The feeding mechanism, by which the main frame casting 8 is rotated to cause the cutter bits 25 to engage the coal, consists of a winding drum 98 upon which is windable a feed rope 99 having a suitable terminal 45 100 adapted to engage with an abutment 101 attached to the bottom pan 1. Sheaves 102, 103 and 104 are provided to guide the rope 99. A sheave 105 is mounted in a castor support 106 having trunnions 107 journaled in bearings of the main frame in such 50 manner that the rope 99 may be led off from the drum in any desired direction. As shown in Fig. 6 the winding drum 98 is mounted upon a vertical shaft 108 journaled 55 in a suitable bearing 109 of the main frame casting. Contained within the body of the drum 98 is a multiple disk friction clutch 110 of well known construction adapted to be controlled by the hand wheel 111 to connect said drum with the vertical shaft 108. Attached to the lower end of the vertical 60 shaft 108 is a worm gear wheel 112 in engagement with the worm 113. The worm 113 is mounted upon a transverse shaft 114 65 journaled in suitable bearings 115 and 116

as shown in Fig. 5. Fixed to the shaft 114 is a ratchet wheel 117 engaged by a pawl 118 carried by the ratchet lever 119 which is oscillatable about the shaft 114. The spring 118' insures the engagement of the 70 pawl 118 with the ratchet wheel 117 in the manner well understood by those well skilled in the art. The ratchet lever 119 is connected by an eccentric rod 120 with the eccentric 121 attached to the power shaft 20. 75 By the rotation of the eccentric 121 the ratchet lever 119 is caused to oscillate, thereby rotating the ratchet wheel 117 with a step by step movement, and, through the worm gears 112 and 113, to drive the winding drum 98. A second pawl 122 supported upon the gear case housing 123, engages the ratchet wheel, 80 to prevent the rotation of the shaft 114 in a direction to unwind the rope. A curved metallic shield 124 adapted to engage the 85 pawl 118 is supported concentrically with the ratchet wheel by an arm 125 pivotally mounted upon the shaft 114 at either side of the ratchet wheel 117. On the arm 125 is formed an extension arm 126 connected by a link 127 with the bell crank 128 attached to the shaft 129 journaled in suitable bearings of the main frame of the machine. The shaft 129 is provided with controlling 90 handles 130, within convenient reach of the hands of the operator, by the manipulation of which the shield 124 may be moved rotatively of the ratchet wheel to engage the pawl 118 during a greater or less portion of its oscillation, thereby controlling the rate of rotation of the ratchet wheel 117 and the consequent rate of winding of the feed rope 98. Attached to the base plate 1 are hinges 131 to which are secured laterally extending arms formed of the angle bars 132 which are adapted to be engaged by suitable anchor jacks to prevent movement of the base plate 1 during the operation of the machine, but as these devices form no part in the present invention further description of them is not 95 thought to be required at this time. 100

When mining by the room and pillar system, at the beginning of each cycle of operation, the machine is placed at a suitable distance from the working face with the cutter arm extending to the right hand side at right angles to the longitudinal lines of the machine. The cutter arm is then elevated to the line of the roof, the feed rope 99 passed around the guide sheaves 102, 103 and 104 from right to left and attached to the abutment 101 of the bottom pan. After starting the cutting mechanism the feeding devices are actuated to wind the rope causing the turn table to rotate in the anti clockwise direction. The cutter bits 25 will then engage the coal to form a kerf above, behind and below a section of the vein to sever a crescent shaped section from the body of the vein. As the cutter arm 110 115 120 125 130

advances fragments of coal will drop by their own weight upon the apron 77 and be gathered by the conveyor flights 44 to be moved rearwardly of the machine. If owing either to the thickness of the section or the hardness of the coal such fragments should fail to drop by their own weight the cutter bits 84 attached to the conveyor flights 44 will engage the partly severed coal section, pry off fragments therefrom and insure breaking up of the coal into fragments of suitable size for loading. After the upper section has been completely removed the cutter arm will be returned to the right hand side of the machine, lowered to the line of the floor and the operation as above described repeated.

What I claim is—

1. In a machine of the class described, the combination of a forwardly extending upwardly inclined cutting mechanism adapted to rotation about a vertical axis to form a kerf in the mine wall, conveying mechanism adapted to follow said cutting mechanism to remove material dislodged from said mine wall said conveying mechanism including a pan curved along transverse lines to conform approximately to the conical surfaces generated by the rotation of said inclined cutting mechanism. 20
2. In a machine of the class described, the combination of a base frame adapted to rotation about a vertical axis, forwardly extending upwardly inclined cutting mechanism mounted upon said base frame and rotatable therewith to form a kerf in the mine wall, conveying mechanism mounted upon said base frame and adapted to follow said cutting mechanism to remove material dislodged from said mine wall said conveying mechanism including a pan curved along transverse lines to conform approximately to the conical surfaces generated by the rotation of said inclined cutting mechanism. 30
3. In a machine of the class described, the combination of a forwardly extending upwardly inclined cutting mechanism adapted to rotation about a vertical axis to form a kerf in the mine wall, conveying mechanism adapted to enter said kerf to receive and remove material dislodged from said mine wall said conveyor including a pan curved along transverse lines to conform approximately to the conical surfaces generated by the rotation of said inclined cutting mechanism. 50
4. In a machine of the class described, the combination of a base frame adapted to rotation about a vertical axis, forwardly extending upwardly inclined cutting mechanism mounted upon said base frame and rotatable therewith to form a kerf in the mine wall, conveying mechanism mounted upon said base frame and adapted to follow said cutting mechanism to remove material dislodged from said mine wall, and devices actuated by said conveying mechanism to dislodge said material. 60
5. In a machine of the class described, the combination of a base frame adapted to rotation about a vertical axis, forwardly extending upwardly inclined cutting mechanism mounted upon said base frame and rotatable therewith to form a kerf in the mine wall, conveying mechanism mounted upon said base frame and adapted to follow said cutting mechanism to remove material dislodged from said mine wall said conveying mechanism comprising an endless chain, flights extending laterally from said chain, and a trough along which said flights are adapted to travel to convey the dislodged material, said trough being curved along transverse lines to conform approximately to the conical surfaces generated by the rotation of said inclined cutting mechanism. 70
6. In a machine of the class described, the combination of a base frame adapted to rotation about a vertical axis, forwardly extending upwardly inclined cutting mechanism mounted upon said base frame and rotatable therewith to form a kerf in a mine wall, conveying mechanism mounted upon said base frame and adapted to enter said kerf to receive and remove material dislodged from said mine wall said conveying mechanism comprising an endless chain, flights extending laterally from said chain, and a trough along which said flights are adapted to travel to convey dislodged material, said trough being curved along transverse line to conform approximately to the conical surfaces generated by the rotation of said inclined cutting mechanism. 80
7. In a machine of the class described, the combination of a forwardly extending cutting mechanism adapted to rotation about a vertical axis to form a kerf in a mine wall, conveying mechanism adapted to follow said cutting mechanism to remove material dislodged from said mine wall, and devices actuated by said conveying mechanism to dislodge said material. 90
8. In a machine of the class described, the combination of a base frame adapted to rotation about a vertical axis, forwardly extending cutting mechanism mounted upon said base frame and rotatable therewith to form a kerf in the mine wall, conveying mechanism mounted upon said base frame and adapted to follow said cutting mechanism to remove material dislodged from said mine wall, and devices actuated by said conveying mechanism to dislodge said material. 100
9. In a machine of the class described, the combination of a base frame adapted to rotation about a vertical axis, forwardly extending cutting mechanism mounted upon said base frame and rotatable therewith to form a kerf in the mine wall, conveying mechanism mounted upon said base frame and adapted to follow said cutting mechanism to remove material dislodged from said mine wall, and devices actuated by said conveying mechanism to dislodge said material. 110
10. In a machine of the class described, the combination of a base frame adapted to rotation about a vertical axis, forwardly extending cutting mechanism mounted upon said base frame and rotatable therewith to form a kerf in the mine wall, conveying mechanism mounted upon said base frame and adapted to follow said cutting mechanism to remove material dislodged from said mine wall, and devices actuated by said conveying mechanism to dislodge said material. 120
11. In a machine of the class described, the combination of a base frame adapted to rotation about a vertical axis, forwardly extending cutting mechanism mounted upon said base frame and rotatable therewith to form a kerf in the mine wall, conveying mechanism mounted upon said base frame and adapted to follow said cutting mechanism to remove material dislodged from said mine wall, and devices actuated by said conveying mechanism to dislodge said material. 130

9. In a machine of the class described, the combination with a base frame adapted to rotation about a vertical axis, forwardly extending cutting mechanism mounted upon said base frame and rotatable therewith to form a kerf in a mine wall, conveying mechanism mounted upon said base frame and adapted to follow said cutting mechanism to remove material dislodged from said mine wall, said conveying mechanism comprising an endless chain, flights extending laterally from said chain, a trough along which said flights are adapted to travel to convey the dislodged material, and devices attached to said flights to engage and dislodge the material above said flights.

10. In a machine of the class described, the combination of a forwardly extending cutting mechanism adapted to rotation about a vertical axis to form kerfs above, behind and below a section of the mine wall, conveying mechanism adapted to follow said cutting mechanism to remove dislodged material, and devices actuated by said conveying mechanism adapted to engage the partially severed section to dislodge fragments therefrom.

11. In a machine of the class described, the combination of cutting mechanism adapted to movement relative to a mine wall to form kerfs above, behind and below a section thereof, conveying mechanism adapted to follow said cutting mechanism to remove dislodged material, and devices actuated by said conveying mechanism adapted to engage the partially severed section and dislodge fragments thereof.

12. In a machine of the class described, the combination with cutting mechanism adapted to form a kerf in the mine wall, of a conveyor adapted to follow in the path of said cutting mechanism, a system of coal engaging devices movable with said conveyor into proximity with the coal above a previously formed kerf, and means to actuate said devices to cause them to engage the coal and dislodge it onto said conveyor.

13. In a machine of the class described, the combination with cutting mechanism adapted to form a kerf in a mine wall, of a conveyor adapted to follow in the path of said cutting mechanism, a system of teeth movable with said conveyor into proximity with the coal above said kerf, and means to impart movement to said teeth to cause them to engage the coal above said kerf to dislodge it onto said conveyor.

14. In a machine of the class described, the combination with cutting mechanism adapted to form a kerf in a mine wall, of a conveyor adapted to follow in the path of said cutting mechanism, a system of teeth movable with said conveyor into proximity with the coal above said kerf, and means actuated by said conveyor to impart move-

ment to said teeth to cause them to engage the coal above said kerf and dislodge it onto said conveyor.

15. In a machine of the class described, the combination with a conveyor comprising a chain and coal transporting devices attached to the said chain, of a system of spurs movable with said conveyor into proximity with a body of coal above a previously formed kerf, and means actuated by said conveyor chain to impart movement to said spurs and cause them to engage the coal above said kerf and dislodge it onto said conveyor.

16. In a machine of the class described, the combination with a conveyor comprising a chain and coal transporting devices attached to said chain, of a system of coal engaging devices comprising sockets and cutter bits removably secured in said sockets movable with said conveyor into proximity with the coal above a previously formed kerf, and means actuated by said conveyor chain to impart movement to said coal engaging devices to cause said cutter bits to engage the coal above said kerf and dislodge it onto said conveyor.

17. In a machine of the class described, the combination with an elongated conveyor having a receiving portion adjacent the mine floor, a system of coal engaging devices movable with said conveyor into proximity with a body of coal above a previously formed kerf, and means actuated by said conveyor to impart motion to said coal engaging devices to cause them to engage the coal above said kerf and dislodge it onto said conveyor.

18. In a machine of the class described, the combination with an elongated conveyor having a receiving portion adjacent the mine floor, of a system of teeth movable with said conveyor into proximity with a body of coal above a previously formed kerf, and means to impart a cutting movement to said teeth to cause them to engage the coal above said kerf and dislodge it onto said conveyor.

19. In a machine of the class described, the combination with cutting mechanism adapted to form a kerf in the mine wall, a conveyor having laterally extending flights adapted to enter said kerf to receive and remove material as it is dislodged from the mine wall, and spurs attached to said flights adapted to engage the material above said kerf to dislodge fragments therefrom.

20. In a machine of the class described, the combination with cutting mechanism adapted to form a kerf in the mine wall, of a simultaneously operable conveyor having laterally extending flights adapted to enter said kerf to receive and remove material as it is dislodged from the mine wall, and spurs attached to said flights adapted to

engage the material above said kerf to dislodge fragments therefrom.

21. In a machine of the class described, the combination with cutting mechanism adapted to form kerfs above, behind and below a section of the mine wall, devices adapted to enter the lower kerf to receive and remove material dislodged from said mine wall, and devices attached to said 10 moving devices adapted to engage the partly severed section and dislodge fragments therefrom.

22. In a machine of the class described, the combination with cutting mechanism adapted to form kerfs above, behind and below a section of the mine wall, a conveyor having laterally extending flights adapted to enter the lower kerf to receive and remove material as it is dislodged from the mine wall, and spurs attached to said flights 15 adapted to engage the partly severed section and dislodge fragments therefrom.

In testimony whereof I affix my signature.

NILS D. LEVIN.
